SKYLIGHT ACTUATING MECHANISM

Filed Aug. 27, 1925

Inventor

Benjamin P. Blaski

By Leslie W. Price

Attorney

UNITED STATES PATENT OFFICE

BENJAMIN P. BLASKI, OF CHICAGO, ILLINOIS

SKYLIGHT-ACTUATING MECHANISM

Application filed August 27, 1925. Serial No. 52,813.

My invention relates to skylight actuating mechanisms and it has for its principal object the provision of a new and improved construction by which the stress upon the movable section of a skylight may be minimized so that the section can be operated substantially without distortion and without breakage, and particularly so that very little, if any, tension will be placed on the section when it is brought to its fully closed position. It is another object of my invention to improve the connections by which power is transmitted for the opening and closing operations from an operating shaft of the section.

It is still another object of my invention to improve devices of this type in sundry details hereinafter pointed out. The preferred means by which I have accomplished my several objects are illustrated in the accompanying drawing and are hereinafter specifically described. That which I believe to be new and desire to cover by this application is set forth in the claims.

In the drawing,—

Fig. 1 is an end view of one side portion of a skylight embodying my improved construction, parts of the structure being broken away and some parts being shown in section.

Fig. 2 is a cross section taken on line 2—2 of Fig. 5.

Fig. 3 is a cross section taken on line 3—3 of Fig. 1.

Fig. 4 is a vertical cross section on an enlarged scale through the pinion by which power is transmitted to one of the operating bars for giving the movable section of the skylight a swinging movement.

Fig. 5 is a view, more or less diagrammatic, showing the position of certain of the parts at the end of the operation of closing the section.

Fig. 6 is a central vertical section through the pinion shown in Fig. 4.

Fig. 7 is a view of the parts shown in Fig. 6 as seen from the left in said figure, but with certain of the parts omitted for clearness of illustration.

Referring now to the several figures of the drawing, in which corresponding parts are

indicated by the same reference characters,— 15 indicates the side sills of the frame of a skylight, having cross bars 16 secured thereon at intervals therealong. Rafters 17 are secured at their lower ends to the cross bars 16 and are secured together at their upper ends, supporting bars 18 being connected with the rafters near their upper ends and being preferably connected with the cross bars 16 at their lower ends (not shown). Extending longitudinally of the skylight at the ridge portion, I have provided a cap 19 supported by the upright bars 18. At each side of the skylight, I provide a movable section comprising a frame supporting one or more sheets of glass 20, each of said sections being provided with a top rail 21, a bottom rail 22 and a plurality of transversely extending bars 23, the glass being secured in the frame work by means of strips 24 which overlie the side edges of the glass. Each section is pivotally supported in position by means of plates 25 secured to the top rail 21 at opposite ends thereof, each of the plates 25 being provided with a lug 26 extending through a suitable opening in the horizontally extending flange of an adjacent rafter 17. By this construction the closure section of the skylight is pivotally supported on the supporting structure so as to be capable of being swung up and down thereon for ventilating purposes. 70

As is clearly shown in Fig. 1, the top bar of the section comprises a flange 27 adapted to rest upon a flange 28 of the ridge cap 19 when the section is in closed position. The bottom rail is likewise provided with a flange portion 29 adapted to be lowered into contact with the side sill 15 of the skylight. 80

The means for raising and lowering the closure section comprises a shaft 30 revolvably mounted upon brackets 31 carried by the cross bars 16. This shaft 30 is provided with pinions 32 fixedly mounted thereon at intervals along the skylight, each of said pinions being provided with an operating bar 33 in the form of a rack meshing with the pinion, said rack bars being adapted upon rotation of the shaft to move the bars 33 longitudinally of themselves for raising the closure section by contact therewith. 90

100

As is best shown in Fig. 1, the upper end of each of the rack bars 33 is connected with the under face of the closure section by means of a link or links 34, such links being pivotally connected in position by means of bolts 35, as shown in Fig. 2.

Referring now particularly to Figs. 4, 6, and 7, each of the pinions 32 comprises a fly wheel 36 preferable in the form of a casting secured by means of a set screw 37 adjustably in position upon the shaft 30. Secured upon one face of the fly wheel 36 are two plates 38 and 39 which are held in spaced relation by means of lugs 40 formed integrally with the plates. These plates are secured to the fly wheel 36 by means of bolts 41 which extend through suitable openings in the plates and are riveted upon the opposite face of the fly wheel, the construction being such that the bolts are rotatable with respect to the plates. As is best shown in Fig. 4, the bolts 41 are arranged in symmetrically spaced position about the axis of the shaft 30 so as to act as teeth for the pinion 32, in the construction shown three of such bolts being provided. Additional bolts 42 are provided in spaced relation between the bolts 41, the bolts 42 being loosely mounted in the plates 38 and 39 so as to be rotatable therein, being held in position by contact with the fly wheel 36.

The rack bars 33 are held in engagement with the teeth of the pinions 32 by means of clips 43 which extend about the rack bars 33 with their end portions mounted upon the shaft 30 on opposite faces of the pinions.

The arrangement is such that at about the time when the closure section reaches its closed position the teeth of the pinions 32 are brought into contact with portions of the rack bars 33 beyond the teeth of the rack bar, as is shown in Fig. 5, so as to prevent further downward movement of the rack bars, the pinions 32 being adjusted with respect to each other about the shaft 30 so as to effect simultaneous stopping action by the several pinions. In case the closure section has been brought to its fully closed position slightly before the stoppage of the rotation of the shaft 30 as described, the rack bars 33 are adapted to move downwardly to a limited extent away from the bottom face of the closure section as is shown in Fig. 5 whereby the bars are prevented from producing any undue strain on the closure section or the supporting structure such as might cause breakage of the parts.

By my construction in which the bolts forming the teeth of the pinion are rotatably mounted, the pinions act very effectively upon the rack bars for the opening and closing operations of the closure section. By the provision of the fly wheel members of the pinions 32, the shaft 30 is given sufficient momentum for assisting in the operation of

the mechanism, and particularly for the closing operation, when the shaft 30 may be spun for effecting an automatic closure of the skylight when it is desired to effect such closure hurriedly. By constructing the pinions 32 in the manner above described, I am enabled to produce such pinions at a comparatively low cost of manufacture, the plates 38 and 39 being preferably duplicates of each other, and the arrangement being such that the improved pinion of the type described can be produced with a minimum of machine work thereon.

As is shown in Figs. 1 and 3, the shaft 30 has a gear 44 fixedly mounted thereon, such gear being driven by a pinion 45 meshing therewith, such pinion being driven by a pulley 46 which in turn is operated by a chain 47.

While I prefer to employ the construction as illustrated in the drawing, I wish to have it understood that I do not desire to be limited to the particular form of construction illustrated except so far as the same is specifically claimed, inasmuch as it is evident that changes may be made in the arrangement without departing from the spirit of the invention.

I claim:

1. In a skylight, the combination of a supporting structure, a closure section swingingly mounted on said supporting structure, a plurality of bars adapted by longitudinal movement in one direction to raise said section, power means for moving said bars in unison, and connections between said bars and said section adapted to hold the bars in position but to permit a limited movement of the bars in the direction away from the section, the arrangement being such as automatically to stop the movement of the bars away from the section shortly after the section reaches its closed position.

2. In a skylight, the combination of a supporting structure, a closure section swingingly mounted on said supporting structure, a link pivotally connected with said section on its bottom face, a bar pivotally connected with said link adapted by contact with the section to move it upwardly, and means for giving said bar a longitudinal movement for swinging the section up and down, said link being adapted to permit limited downward movement of the bar independently of movement of the section, the engagement between said bar and the means by which the bar is actuated for swinging the section serving to stop the downward movement of the bar at the end of the closing movement of the section for preventing the application of a heavy downward pull through said bar on said section.

3. In a skylight, the combination of a supporting structure, a closure section swingingly mounted on said supporting structure, a shaft revolvably mounted parallel with said

section, pinions fixedly mounted on said shaft, means for rotating said shaft and pinions, rack bars meshing with said pinions and adapted upon rotation of the shaft to swing said section upwardly into opened position, and means serving to stop the downward movement of the rack bars at approximately the time when the section reaches its closed position, said rack bars being adapted to have a limited downward movement with respect to the section at the end of the operation of closing the section.

4. In a skylight, the combination of a supporting structure, a closure section swingingly mounted on said supporting structure, a shaft revolubly mounted parallel with said section, pinions fixedly mounted on said shaft, means for rotating said shaft and pinions, rack bars meshing with said pinions and adapted upon rotation of the shaft to swing said section upwardly into opened position, and means serving to hold said rack bars from swinging out of engagement with the pinions, the arrangement being such that the engagement of the bars beyond the teeth thereon with the teeth of the pinions serves to stop the downward movement of the rack bars at approximately the time when the section reaches its closed position and that said bars are adapted to have a limited downward movement with respect to the section for preventing tension on the section in case the downward movement of the bars continues slightly after the completion of the closing operation.

5. In a skylight, the combination of a supporting structure having an opening therethrough, a closure section swingingly mounted on said structure adapted upon a downward swinging movement to close said opening, a link pivotally connected with said section on its under face, a bar pivotally connected with said link adapted by engagement with said section upon upward movement of the bar to press upwardly on said section for raising it and adapted upon its downward movement to move out of operative engagement with the section at the end of the closing movement of the section, and means for giving said bar alternative up and down movements.

BENJAMIN P. BLASKI.
